UNITED STATES PATENT OFFICE

152,657

DESIGN FOR A FISH LURE

Stephan J. Simon, Detroit, Mich.

Application March 23, 1948, Serial No. 145,280

Term of patent 14 years

(Cl. D31—4)

To all whom it may concern:

Be it known that I, Stephan J. Simon, a citizen of the United States, residing at Detroit, in the county of Wayne and State of Michigan, have invented a new, original, and ornamental Design for a Fish Lure, of which the following is a specification, reference being had to the accompanying drawing, forming part thereof.

I claim:

The ornamental design for a fish lure, as shown.

STEPHAN J. SIMON.
